Primary Examiner — W. A. Teddy Falloway

(74) Attorney, Agent, or Firm — Morland C. Fischer

CLAIM

The ornamental design for a food holder with cup, as shown and described.

DESCRIPTION

FIG. 1 is a perspective view showing the top, front and right side of a food holder with cup, which forms my new design; FIG. 2 is a top plan view thereof;

FIG. 3 is a front elevational view thereof;

FIG. 4 is a left side elevational view thereof;

FIG. 5 is a right side elevational view thereof;

FIG. 6 is a rear elevational view thereof; and,

FIG. 7 is a bottom plan view thereof.

1 Claim, 3 Drawing Sheets
